UNITED STATES PATENT OFFICE.

MONTRAVILLE M. WOOD, OF SCHENECTADY, NEW YORK, ASSIGNOR TO
GENERAL ELECTRIC COMPANY, A CORPORATION OF NEW YORK.

SNAP-SWITCH.

No. 825,259.

Specification of Letters Patent.

Patented July 3, 1906.

Application filed November 7, 1903. Serial No. 180,252.

To all whom it may concern:

Be it known that I, MONTRAVILLE M. Wood, a citizen of the United States, residing at Schenectady, in the county of Schenectady and State of New York, have invented certain new and useful Improvements in Snap-Switches, of which the following is a specification.

The object of my invention is to provide an electric snap-switch in which the movable contact member is normally locked in either its extreme open or closed position and moved from one to the other by a positive snap action, so that injury to the contact parts from electric arcing by the parts remaining for a perceptible period in an intermediate position is prevented.

A further object of my invention is to provide an electric snap-switch in which the several operative parts are so designed and arranged that they may be made of metal punchings and without expensive machining and in consequence of which the cost of manufacture is greatly reduced.

The invention will be readily understood upon reference to the following description and the accompanying drawings, forming a part of this specification, in which—

Figure 1 is a vertical longitudinal section of the inclosing box and operative parts of the two-button snap-switch embodying my invention with the parts shown in their respective positions at the instant of closing. Fig. 2 is a similar section of the box with the operative parts shown in locked position, and Fig. 3 is an end elevation of the operating parts with the blades and their insulating connections to the switch-shaft shown in section.

The inclosing shell or box A is made of porcelain and provided with the usual apertures for leading in the conductor-wires. To the inner end walls of the box are secured metallic binding-posts B, to which the stationary contacts C are secured. Across the open side of the box A is attached the supporting-plate D, and overlying the plate and constituting a finished covering for the box is the face-plate E, in which are provided suitable holes for the passage of the push-buttons F.

In the present constructions two switch-blades 1 and 2 are employed, each non-rotatively connected through insulation 3 to a

horizontal shaft 4, which is journaled in an arm 5, depending from the center of an edge of the supporting-plate D. The arm 5 is provided with a fixed bushing 6, which affords a long bearing for the shaft, and below the bushing it is extended sidewise and has formed therein a segmental slot 7, concentric with the axis of the bearing. On the outside of the bushing 6 is a sleeved bearing 8, to which a rocking lever 9 is attached. The rocking lever is pivotally connected at each end to a metal bracket 10, secured to the inner end of a push-button F, and is provided at its lower edge with an arm 11, bent up parallel to the shaft 4, and at its upper edge with a series of gear-teeth 12.

A latch-plate 13 is mounted upon the shaft 4, between the end of the bushing 6 and the insulation 3 at the right-hand end thereof, and secured to rotate with the shaft by a pin 14, extending into the insulation. The lower end of the latch-plate is provided with an arm 15, bent parallel to the shaft, so as to swing in a path just below that of the arm 11 of the rocking lever, and extends through the slot 7, so as to abut at either end of its oscillation against the radial ends of said slot. The upper end of the latch-plate extends upwardly a considerable distance and is bent in the same direction as arm 15 and provided at its end with a shoe 16, which engages stops 17, carried by an oscillating plate 18. The oscillating plate is journaled upon a stub-shaft 19, carried by the arm 5, and consists of a metal punching of disk shape with gear-teeth 20 formed in its lower edge, which mesh with the teeth formed on the upper edge of the rocking lever 9. The stops 17 are formed at diametrically opposite points by bending up short arms at right angles to the plane of the plate and removing their inner corners.

A helical spring 21 surrounds the sleeve 8 and has its opposite ends extended outward and crossed, as indicated in Fig. 1, so as to engage the opposite edges of arms 11 and 15 of the rocking lever and the latch-plate and operating thereon to normally hold them in alinement.

The operation of the device above described is as follows: When the parts are at rest, the shoe 16 of the latch-lever is, as will be explained later, in engagement with the outer surface of one of the stops 17 and is thereby

prevented from moving when the push-button F on the opposite end of the switch is being forced inward from its outermost position to near its extreme inner position, thereby putting the spring 21 under tension. As the button reaches its innermost position the oscillating plate 18, which is geared to the rocking lever 9 to move simultaneously therewith, carries the stop 17, with which the latch-lever was in engagement, out of the path of the shoe 16 and allows the latch-lever and the switch-blades 1 and 2 connected therewith to move with a snap action under the recoil of the spring into their opposite positions. In Fig. 1 the parts are shown in their respective positions just after the switch-blades have moved into closed position with the left-hand button in its extreme inner position. It is to be noted that the latch-lever 13 is arrested by contacting with the end of the segmental slot 7 before its arm 15 reaches alinement with arm 11 of the rocking lever, so that when pressure is removed from the button the spring 21 acts automatically to move the rocking lever 9, and with it the oscillating plate 18, backward a slight distance, thereby bringing a stop 17 into the path of the shoe, as shown in Fig. 2.

I do not wish to restrict myself to the particular construction or arrangement of parts herein described and shown, since it is apparent that they may be changed and modified without departing from my invention.

What I claim as new, and desire to secure by Letters Patent of the United States, is—

1. In an electric snap-switch, the combination of a switch-blade, a locking member connected to move therewith, a rocking lever pivoted coaxially with the switch-blade, a spring connecting the locking member and the lever, and a pivoted member connected to move simultaneously with said lever and provided with retaining devices adapted to oppose the movement of the locking member during the movement of the rocking lever through a predetermined angle.

2. In an electric snap-switch, the combination of a pivoted switch-blade, a locking member connected to rotate therewith, a rocking lever pivoted coaxially with the switch-blade, a spring normally operating to hold the locking member and the lever in definite angular relation, and a pivoted member connected to move simultaneously with said rocking lever and provided with retaining devices adapted to traverse the path of movement of said locking member.

3. In an electric snap-switch, the combination of a pivoted switch-blade, a locking member connected to move therewith, a rocking lever pivoted coaxially with said parts, a spring normally operating to hold

the locking member and the lever in definite angular relation, an oscillating member pivoted about a fixed axis parallel to the axis of the other parts and provided with retaining devices adapted to traverse the path of travel of said locking-lever, and means for moving said oscillating member concurrently with the movement of said rocking lever.

4. In an electric snap-switch, the combination of a pivoted switch-blade, a locking-blade rigidly connected thereto and provided at one end with an arm and at the other with an offset projection, a rocking lever pivoted coaxially therewith and provided with an arm, a spring normally acting to hold the arms of the locking-blade and the lever in alinement, and an oscillating plate connected to move simultaneously with said lever and provided with projections adapted to engage the offset end of the locking-blade and hold it in either extreme position while the rocking lever is being moved to its corresponding opposite position.

5. In an electric snap-switch, the combination of a pivoted switch-blade, a locking member connected to move therewith, a rocking lever pivoted coaxially with said parts and provided at one edge with gear-teeth, a spring normally acting to hold the lever and the locking member in a definite angular position, and an oscillating member having gear-teeth meshing with the corresponding teeth of said lever and provided with projections adapted to engage an end of the locking member during a predetermined angular movement of the rocking lever.

6. In an electric snap-switch, the combination of a support provided with a segmental slot, a shaft journaled in said support, a switch-blade mounted on the shaft, a locking-blade rigidly connected to said switch-blade and provided at one end with an arm extending into said segmental slot and at its opposite end with an offset, a rocking lever having an arm in proximity to the arm of said locking-blade, a spring normally acting to hold the arms of the lever and the locking-blade in alinement, and an oscillating member connected to move simultaneously with the rocking lever and provided with projections adapted to engage the offset end of the locking-lever and hold it from movement during the movement of the rocking lever from one extreme position to the other.

In witness whereof I have hereunto set my hand this 6th day of November, 1903.

MONTRAVILLE M. WOOD.
